GIRL'S BICYCLE FRAME

Viktor Schreckengost, Cleveland Heights, Ohio, assignor to The Murray Ohio Manufacturing Company, Nashville, Tenn., a corporation of Ohio

Application March 3, 1958, Serial No. 49,875

Term of patent 14 years

(Cl. D90—8)

Fig. 3

Fig. 1 is a view slightly in perspective of a girl's bicycle frame showing my new design;

Fig. 2 is a right side elevation thereof; and

Fig. 3 is a top plan view of Fig. 2.

I claim:

The ornamental design for a girl's bicycle frame, substantially as shown.
